(57) **CLAIM**

The ornamental design for a notebook computer as shown and described.

DESCRIPTION

FIG. 1 is a perspective view of a notebook computer showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is an enlarged view of the portion, labeled '8' in FIG. 6.

The design consists of the features of the shape, ornament, pattern and configuration of a notebook computer as shown in the drawings. The even-dashed broken lines illustrate portions of the notebook computer that form no part of the claimed design. The dot-dot-dash broken line in FIG. 6 and FIG. 8 indicates cutoff boundaries for enlarged detail portion views and form no part of the claimed design.
